UNITED STATES PATENT OFFICE

155,511

DESIGN FOR AN EAR PENDANT

Josef Janousek, Vienna, Austria

Application May 5, 1949, Serial No. 2,469

Term of patent 3½ years

(Cl. D45—9)

To all whom it may concern:

Be it known that I, Josef Janousek, a citizen of Austria, residing at Vienna 1, Spiegelgasse 2, Austria, have invented a new, original, and ornamental Design for an Ear Pendant, of which the following is the specification, reference being had to the accompanying drawing, forming a part thereof.

In the drawing:

I claim:

The ornamental design for an ear pendant, as shown.

JOSEF JANOUSEK.
